UNITED STATES PATENT OFFICE.

KARL RÖGER, OF BERLIN, GERMANY, ASSIGNOR TO MERGENTHALER LINOTYPE COMPANY, A CORPORATION OF NEW YORK.

TYPOGRAPHICAL MACHINE.

1,105,702.

Specification of Letters Patent.

Patented Aug. 4, 1914.

Application filed January 2, 1914. Serial No. 809,852.

To all whom it may concern:

Be it known that I, KARL RÖGER, a subject of the German Emperor, residing at 9 Katsbachstrasse, Berlin, in the Empire of Germany, have invented new and useful Improvements in Typographical Machines, of which the following is a specification.

Line producing machines are known which are adapted to compose and use a typographical line in mixed faces, one of which is the normal face and the other or others of them, variants therefrom. The pieces used in such machines, *e. g.*, the matrices of the well known matrix composing and line casting machine sold under the trade mark "Linotype", have one or more variant faces arranged columnwise above the normal face and in the same edge of a matrix. Each matrix is a flat oblong plate, the opposite shorter edges of which are respectively its top and bottom. A plate constitutes the body of a matrix and has a lug projecting from each corner in its own plane. The two top lugs are of the same size with their top faces flush with the top of a plate and the bottom faces of the bottom lugs, flush with the bottom of a plate.

The above mentioned plurality of faces imposes the following requirements—first, 30 means for adjusting the level of each matrix at the place of composition, so as to place the desired variant face in the composing line; second, means for holding all the matrices in the typographical line, in the respective positions during the time that the said line is being used, *e. g.* having a line produced from it by casting as in the machine instanced; and thirdly, means for restoring all the adjusted matrices to the normal level so as to adapt them to be dealt with by the distributor. These last mentioned means consist in the machine instanced, in a leveling bar and the means for holding the adjusted matrices being a ledge 40 for each level, engaging under their bottom front lugs, and automatically retractable from thereunder as the means which hold all the matrices moves away from the using position toward the distributor. The adjusting motion above mentioned as being made at the place of composition, is an upward one and when it has been made, the bottom edges of the top lugs of the adjusted, *i. e.*, variant, matrices and the top edges of

those of the unadjusted, *i. e.*, normal matrices, are either in the same horizontal plane or they overlap each other. Several means have been proposed to meet these requirements, and at least one meeting each requirement, is in use in the machine instanced when it is equipped with matrices having two faces. The means for holding all the matrices in the line, in the respective positions, during the time the said line is being used, are a ledge engaging under each top lug of the normal *i. e.*, unadjusted matrices and a third ledge engaging under the front bottom lug of each variant *i. e.*, adjusted matrix, so that it is not the whole of the last mentioned lug but only its bottom face that can affect such holding. But these bottom faces get worn by repeated hard contacts with certain parts of the machine, to an extent sufficient to put the respective variant faces out of adjustment when the said bottom faces are on the ledge.

The object of the present invention is to prevent the wear just described so thwarting the desired adjustment of the variant faces. It has already been proposed to prevent this thwarting by prolonging the third ledge and front bottom lug, either or both, in such a way that the lug shall either present to the ledge, a portion of bottom face that has not come into such contact with any part of the machine, or that the ledge shall engage with the foot of the body of the matrix, in either of which cases, no wear which the bottom face of the lug may have suffered, can be material. It has also been proposed to hold the adjusted *i. e.*, variant matrices during the time the typographical line is being used, by a rail automatically engaged under each of their top lugs and automatically disengaged therefrom after such use, both engagement and disengagement being in the direction of the length of the two rails; or by a ledge standing in front of the line and so connected with the same for restoring all the adjusted matrices to the normal level, that it automatically engages in a notch common to all the front top lugs of the said matrices and is automatically disengaged therefrom as the typographical line is moved away toward the distributor.

The present invention consists in reducing the vertical dimension of the top front lug of each matrix more or less, say by

about one half, so that there shall be a space between the top front lugs of the adjusted matrices and those of the normal matrices, this space embracing a ledge having the functions of the third ledge already described and suitably positioned to be so embraced. Thus the lug surface that engages the ledge is one which enjoys, by reason of its being a bottom face of a top lug, immunity from the wear described. If there is a plurality of variant faces, there is a corresponding plurality of reduced top front lugs and spaces arranged columnwise on the matrices. The ledge just described is a single one and will in any case be embraced by the lowest space. But it will be understood that a greater number of ledges may be provided to correspond to the number of variant faces on the matrices.

20 The accompanying figures illustrate two preferred constructional forms of the invention when applied to a machine of the kind instance and equipped with matrices having one variant face.

25 Referring to them, Figure 1 is a vertical section looking from the right hand side of the machine and showing the parts of one constructional form in the casting position; Fig. 2, a like section showing the variant face pieces restored to the normal level; Fig. 3, a side elevation of one form of matrix; Fig. 4, a section as Fig. 1, of the other form; and Fig. 5, a side elevation of a modified form of matrix.

30 a is the mold wheel, carrying the mold block b having the mold cavity b¹ against which the head c of the so called first elevator is holding the typographical line consisting of matrices d both normal and variant, the normal matrices engaging by their top front lugs on a rail m, while the bottom rear lugs i of both normal and variant matrices engage loosely, i. e., without being held, respectively in a plate k fast to the mold block b and under

35 the latter. The ledge e is loosely connected to a lever f and slides horizontally in the head c, being protruded by a spring g into the path of the adjusted line before it is pushed into the head c. As the said line is being moved toward the distributor (not shown), the ledge e is disengaged from the variant matrices, by the engagement of the lever f with an abutment n on the machine, whereupon the said matrices are restored to

40 the normal level partly by their own weight and partly by an overlying bar o, all as heretofore.

Figs. 1 and 3 to 5 show the upper face d¹ of the normal matrices and the lower faces d² of the variant matrices registering properly with the mold cavity b¹ and also that relying upon the engagement of the bottom of the front bottom lugs of the variant matrices with the top of an underlying ledge 65 to keep their lower faces d² in register with

the mold cavity b¹ must fail proportionately to the amount of wear which those bottoms had suffered.

According to the constructional form shown in Figs. 1 to 3, the vertical dimension of the top front lug h of every matrix in a font is reduced at its bottom face, as a comparison of the said lug in Fig. 3 with the top rear lug, shows, so that the top front lugs of the normal and variant matrices of the typographical line will stand in two parallel rows as indicated in Figs. 1 and 4, with a space p between them. The known ledge e is now so positioned in the head c as to register with this space, so that when the said line is pushed into the head c, the bottom faces of the lugs h on the variant matrices, will engage on and be held by the ledge e in the line casting position, while the lugs h on the normal (or any matrices occupying a lower level) will stand under the said ledge and clear of it.

The constructional form illustrated in Fig. 4 and 5 differs from the one just described only in the vertical dimension of the top front lugs h being reduced at its top face. The way in which the present invention deals with a font having a plurality of variant faces, has been already explained. The position of the second lug h¹ required by an additional variant face, is indicated by dotted lines in Figs 3 and 5.

The terms "matrix", "matrices" are to be understood throughout this specification and the following claims as respectively including "type die", "type dies".

Having described my invention, I declare that what I claim and desire to secure by Letters Patent is:—

1. In means for holding the variant face matrices of a mixed typographical line in position for being used in a line producing machine, the combination with a font of matrices having reduced lugs so positioned thereon that the vertical adjustment of the matrices according to face, arranges the said lugs in rows separated by a space, of a ledge upon which the said lugs of the elevated matrices rest and under which those of the unelevated matrices stand clear.

2. In means for holding the variant face matrices of a mixed typographical line in position for being used in a line producing machine, the combination with a font of matrices having reduced lugs so positioned thereon that the adjustment of the matrices according to face, arranges the said lugs in rows separated by a space, of a ledge upon

which the co-operating row of lugs on the adjusted matrices rest and under which those of the matrices at a lower level in the line, stand clear.

3. In a typographical casting machine, the combination of a mold, a line of matrices each formed with a projecting ear at its

upper end, and means for supporting the matrices at different levels in front of the mold and movable to effect their alinement therewith, the said means comprising a 5 ledge to engage beneath the upper ears of the matrices in elevated position, and the matrices having their projecting ears of reduced size and so located as to avoid the supporting ledge when standing in the lower 10 position.

4. In a typographical machine, comprising matrices each formed with a projecting ear at its upper end, the combination of the mold, and the first elevator to present the 15 matrices to the mold and movable to effect their alinement therewith, the said elevator being provided with a ledge to engage beneath the upper ear of the matrices in elevated position, and the matrices having 20 their projecting ears of reduced size and so located as to avoid the supporting ledge when standing in the lower position.

5. In a typographical machine, the combination of a line of matrices each formed

with a projecting ear at its upper end, and 25 means for supporting the matrices at different levels, the said means comprising a ledge to engage beneath the upper ears of the matrices in elevated position, and the matrices having their projecting ears of reduced size 30 and so located as to avoid the supporting ledge when standing in the lower position.

6. In a typographical machine, the combination of a line of matrices each formed with a projecting ear at its upper end, and 35 means for supporting the matrices at different levels, the said means comprising a ledge to engage beneath the upper ears of the matrices in elevated position, and the matrices having the upper portions of their ears cut 40 away to avoid said ledge when they stand in the lower position.

In witness whereof I have hereunto set my hand in the presence of two witnesses.

KARL RÖGER.
